UNITED STATES PATENT OFFICE.

JOAO BAPTISTE LOUREIRO, OF PARA, BRAZIL.

CAN-OPENER.

1,073,502.

Specification of Letters Patent.

Patented Sept. 16, 1913.

Application filed February 26, 1913. Serial No. 750,753.

To all whom it may concern:

Be it known that I, Joao B. LOUREIRO, a citizen of the State of Para, and a resident of Para, in the Republic of Brazil, South America, have invented a new and Improved Can-Opener, of which the following is a full, clear, and exact description.

Among the principal objects which the present invention has in view are: to provide an apparatus of the character mentioned, to cut the extended edge of the head or top of a can, to permit the removal thereof; and to provide an apparatus of the character named, which is simple, efficient, and convenient in operation.

One embodiment of the present invention is to be found in the accompanying drawings forming a part of this specification, and in which—

20. Figure 1 is a top view of a can, showing in connection therewith an opener constructed in accordance with the present invention; Fig. 2 is a side view of the same; Fig. 3 is a detail view on an enlarged scale, showing the end of an opener, constructed in accordance with the present invention, and in conjunction therewith a fragment of a can having a rolled or crimped-edged cover.

As seen in the accompanying drawings, 30 the apparatus is constructed in a manner similar to the construction of conventional pliers. The mated handles 8 and 9 are pivotally connected by a pin 10, and are normally spread by a flat spring, 11. The 35 end of the handle 9 is provided with a bracketed jaw 12, the inner edge of which is shaped to form a sharp, blunt shoulder to form a shearing member to operate in conjunction with a blade 13. Between the 40 jaw 12 and the head 14 is formed a groove or channel 15, into which the blade passes. The blade 13 is shortened relative to the channel 15, so that the face of the head 14 impinges upon the face of the head 16 45 formed on the handle 8.

Laterally extending from the head 16 is the blade 13, which registers in the manner above noted, with the jaw 12. The blade 13 is provided with a relatively sharp cutting 50 edge curved to form a quarter segment of a circle. The curve of the blade 13 is out-

ward or toward the ends of the heads 14 and 16. The inner edge or end of the blade 13 is coincident with the straight edge 17 of said blade. The junction of the straight edge and curved edge of the blade 13 forms a pricking point, which radially penetrates the rolled edge 18, which in conventional constructions is double, being formed by a thickness of the can top or cover 19 and the side 20 thereof. The force applied to close the blade 13 upon the jaw 12 is proportioned to the length of the handles 8 and 9.

In operation, the spring 11 normally opens 65 the heads 14 and 16, the jaw 12 and blade 13 connected therewith. The operator rests the jaw 12 and the flat surface thereof upon the top of the cover 19, and moves the tool toward the can, until the flat side of the 70 blade 13 rests against the side 20 of the can. It will now be found that the blade 13 is disposed below the rolled or crimped edge 18. When the handles 8 and 9 are retracted, the head 16 is moved upward, the 75 sharp edge of the blade 13 wedging between the roll of the edge 18, opening the same from the side of the can, until the metal composing the edge is caught between the shearing edge of the jaw 12 and the cutting edge of the blade 13. At this point, 80 it will be found that the sharp point or junction of the curved edge of the blade and the straight edge 17 thereof is presented to the metal. This point is rigidly 85 forced through the metal, when thereafter the curved edge, rising, cuts the metal forwardly. The tool is now employed in a manner usual to pliers or cutting tools of 90 analogous use and construction.

Having thus described my invention, I claim as new and desire to secure by Letters Patent:—

A can opener, having a plurality of pivotally connected handles; a head mounted 95 on one of said handles, having a laterally-extending bracketed jaw partly separated from said head to form a channel therebetween, the edge of said jaw adjacent said channel forming a shearing member; and a 100 blade laterally extended from the end of the other of said handles to enter said chan-

nel, said blade having a cutting edge to register with the shearing edge of said bracketed jaw, the cutting edge of said blade resting normally inside of said channel and above said shearing edge of said bracketed jaw.

In testimony whereof I have signed my

name to this specification in the presence of two subscribing witnesses.

JOAO BAPTISTE LOUREIRO.
